Patented June 26, 1928.

1,674,980

UNITED STATES PATENT OFFICE.

WILLIAM H. MILLSPAUGH, OF SANDUSKY, OHIO, ASSIGNOR TO THE PAPER & TEXTILE MACHINERY COMPANY, OF SANDUSKY, OHIO.

NEWSPRINT PAPER.

No Drawing. Original application filed January 3, 1923, Serial No. 610,538. Divided and this application filed April 4, 1927. Serial No. 181,903.

Paper on which newspapers and other similar cheap publications are printed is a medium light or light weight paper made from comparatively cheap stock. The stock 5 now commonly used for newsprint paper is largely ground wood pulp fortified by sulphite or other stronger pulp in a proportion usually ranging from about 20 percent sulphite down to as low as 10 percent sulphite, although in some instances newsprint 10 papers have been made without any sulphite where a special ground wood stock was properly prepared. The present standard weight for newsprint paper in the 15 United States is 32 pounds per ream (500 sheets, size 24" by 36"), with a range of from 31 to 33 pounds; though of course such paper may be made in lighter or heavier weights. In Europe newsprint paper is 20 made in weights as light as 25 pounds per ream. What is practically a lighter newsprint paper, made from the same kind of stock with only a little more sulphite, is that known as news catalog, which is used 25 for cheap catalogs such as those published by mail order stores, and which is made in weights ranging from 19 pounds to 25 pounds per ream.

I produce paper of the aforesaid class 30 made from the same stock as the ordinary such paper would be made, and without in any way changing or affecting the stock I obtain a better paper which in comparison with ordinary such paper of the same thickness and composition is materially stronger 35 so that it is better adapted for use in high speed printing presses, or in other words may be run through such high speed printing presses without danger of breakage or 40 with considerably less liability of breakage. This greater strength is obtained by a laminated structure of the sheet of newsprint or similar paper, the sheet being made by simultaneously forming from the stock continuous thin wet paper films and welding 45 these films in a unitary sheet of no greater thickness than the sheet would ordinarily be made. For instance, in making newsprint paper of the ordinary composition and thickness of United States standard weight 50 newsprint paper, I produce from the ordinary newsprint stock two continuous wet films or sheets of half the thickness that the wet sheet would be for making the ordi-

nary such paper and bond these together 55 as a single sheet, thereby obtaining the strengthening effect of the laminated formation and resulting in a newsprint paper of ordinary thickness and composition but which may be safely run through high 60 speed printing presses without breakage and which also has the advantage of better edging.

The paper may be made by flowing the ordinary pulp solution against cylindric 65 forming surfaces provided by suitable mediums such for instance as fine wire cloth traveling on or over suction rolls and inducing the formation of the thin paper films or plies on the mediums by suction, reducing 70 the moisture content of the films or plies by suction, preferably regulated to bring the sheets to the best moisture for good bonding, i. e. containing ample water for bonding purposes but not an undesired 75 excess of water, carrying the sheets by said mediums into contact with one another and bonding them in a unitary sheet and then pressing the sheet and delivering it to dryers. Processes and apparatus by which the 80 paper may be made are described in my copending applications Serial Nos. 610, 538 and 610,539 filed January 3, 1923 and Serial No. 29,600 filed May 11, 1925, this application being a division of the first mentioned application. In said pending applications the processes and means therefor 85 herein described are broadly claimed.

Among other advantages of the duplex newsprint paper, is that it may be made of 90 lighter weight per ream of a given furnish than ordinary newsprint paper. By furnish is meant the kind of stock and percentages thereof which go into the beaters. Newsprint or similar paper according to 95 this invention made from a given furnish will be as strong as a thicker or heavier sheet of ordinary such paper made from the same furnish, or as strong as ordinary newsprint paper of similar weight made 100 from more expensive stock. Thus for a desired strength a cheaper furnish may be used and a lighter paper made than would be necessary for the ordinary newsprint or similar paper of such strength.

I claim as my invention and desire to secure by Letters Patent:

1. As a new product, newsprint paper

made of ordinary stock and thickness but of greater strength than ordinary newsprint paper by simultaneously forming wet sheets of half the thickness of the ordinary wet sheet and consolidating them as a single sheet, thereby obtaining the strengthening effect of a laminated formation.

2. Newsprint or similar paper composed of originally separately made films or plies bonded in a unitary sheet.

3. Newsprint or similar paper made from the same stock as and of no greater thickness than ordinary such paper of similar strength would be made, and composed of integrated separately formed plies.

4. Newsprint or similar paper of laminated formation.

In testimony whereof, I have signed my name to this specification.

WILLIAM H. MILLSPAUGH.
